LUMINAIRE

Viktor Schreckengost, Cleveland Heights, Ohio, assignor to Holophane, Inc., New York, N.Y., a corporation of Delaware

Filed Jan. 6, 1960, Ser. No. 58,942

Term of patent 14 years

(Cl. D48—31)

Fig. 1 is a perspective view of a luminaire showing my new design;

Fig. 2 is a side elevational view thereof with the bracket arm fragmentarily shown for convenience of illustration; and

Fig. 3 is a top plan view thereof as shown in Fig. 2.

The dominant features of my design reside in the portions shown in full lines.

I claim:

The ornamental design for a luminaire, as shown and described.
